UNITED STATES PATENT OFFICE.

WALTER H. WILLIAMS, OF WAUSEON, OHIO.

FLOUR-DRESSING MACHINE.

SPECIFICATION forming part of Letters Patent No. 326,893, dated September 22, 1885.

Application filed March 24, 1885. (No model.)

To all whom it may concern:

Be it known that I, WALTER H. WILLIAMS, a citizen of the United States, residing at Wauseon, in the county of Fulton and State of Ohio, have invented certain new and useful Improvements in Flour-Dressing Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention has relation to flour-bolts, and has for its object to provide a simple construction by which the flour being bolted is separated into a number of small portions in order that every part of same may be more thoroughly subjected to the bolting action.

20 It has for further objects convenient constructions for feeding the several portions of flour into their respective compartments, and other improvements.

25 To these ends the invention consists in certain novel constructions and combinations of parts, which will be more fully described hereinafter, and specifically pointed out in the claims.

30 In the drawings, Figure 1 is a side view of my bolt, partly broken away. Fig. 2 is a longitudinal section on line $x-x$, Fig. 1. Fig. 3 is a transverse section on line $y-y$, Fig. 1; and Fig. 4 is a view of the front or receiving end of the bolt.

35 I have shown my bolt as of equal diameter from end to end, and in the use of it I prefer to support it on an inclined axis. It is manifest, however, that the bolt may be supported on a horizontal axis, and be enlarged or tapered toward its discharge end without departing from the principles of my invention.

40 In carrying out my invention I employ a central core, A, preferably hollow, as shown, and provided with end plates, A' A', having bearings A² for the shaft of the bolt. The front end plate, B, is provided with an opening, C, through which the flour is fed into the bolt. This front plate is arranged parallel to, 45 concentric with, and but a short distance from the front end plate of the core A, and it is

made larger than the said core, so that its edges extend radially beyond the core A.

A cylinder, E, connects the front end of the core A with the front plate, C, and is provided with openings E', which lead into the compartments of a bolting-chamber. This cylinder E is usually and preferably an extension of the cylindrical portion of the core A.

55 Partitions F extend longitudinally along the core A from end to end of the bolt. These partitions are preferably six in number; but it is manifest that the number may be varied without departing from the principles of the invention.

60 The bolting-cloth is placed on the bolt over the partitions F. Thus the chamber for bolting is formed between the core A and the cloth, and the said chamber is divided by the partitions F into a plurality of longitudinally-extended compartments.

65 It will also be noticed that the openings E' lead one into each compartment G, formed by the partitions F, so that as the unbolted flour is fed through the opening C into the space between the plate B and the front of the core A it passes through the lowermost opening E' into the lower compartment G, and as the bolt is revolved each compartment receives 70 its portion of flour, which then passes on toward the discharging end of the bolt, being subjected meanwhile to the bolting-action, as will be seen.

75 When the bolting-chamber is formed an annulus, and the flour is fed in quantities thereinto, it becomes massed, and as the bolt is revolved the portion carried up by the bolt falls back and the massing is continued, only a small portion of the flour being bolted, rendering the operation tedious and requiring repetitions of the process before the desired results are obtained.

80 By my construction the flour to be bolted is divided into small portions, each of which has its own compartment, so that every part of 85 each portion is thoroughly subjected to the bolting-action and speedy results are obtained.

85 In the revolution of the bolt the portion of flour in each compartment G, as the said compartment rises, falls to the lower side thereof, 90 and as the said compartment passes beyond the vertical the flour falls to the opposite side

of the compartment, forming a cloud, which assists the bolting process, and when the said compartment is at its lowest point the flour therein is distributed over its bolting-cover.

5 Thus it will be seen each portion of flour is kept in almost a constant state of agitation, enabling the rapid and thorough bolting of same.

Having thus described my invention, what I claim, and desire to secure by Letters Patent, is—

1. In a flour-bolt, the combination of a reel-frame and bolting-cloth, a central core or drum having a diameter a little less than the diameter of the bolting-reel, and a series of longitudinal radial partitions projected from its periphery, whereby a series of shallow bolting-compartments is formed between the said drum and the bolting-cloth, substantially as set forth.

20 2. The combination, in a flour-bolt, of the bolting-reel, the inner core or drum, the front end plate, B, having a feed-opening and ex-

tended radially beyond the core or drum, and the cylinder E, extended between the front end of the core and the plate B, and the partitions F, extended longitudinally of the core, the cylinder E being provided with openings E' between each of the partitions F, substantially as set forth.

3. The combination, in a flour-bolt, of the bolting-reel, the core having end plates provided with bearings for the supporting-shaft, the front plate, B, having a feed-opening, the cylinder E, connecting the front end of the core and the plate B and provided with openings E', and the longitudinally-extended partitions F, dividing the bolting-chamber into compartments, substantially as set forth.

In testimony whereof I affix my signature in presence of two witnesses.

WALTER H. WILLIAMS.
